UNITED STATES PATENT OFFICE

COURTNEY N. MITCHELL, OF CLEVELAND, OHIO

DOORCHECK

Application filed August 19, 1927. Serial No. 214,043.

This invention relates to door checks or door closers and the main object of the invention is to provide a simple and efficient door check which is adapted for use with either right hand or left hand doors without a change or substitution of parts.

Another object of the invention is to provide a door check of the character described which comprises comparatively few parts, which are readily assembled and disassembled and which is well adapted for quantity production at comparatively low cost.

Further and more limited objects of the invention will appear as the description proceeds and by reference to the accompanying drawings in which Fig. 1 is a view in side elevation of my improved door checks; Fig. 2 a vertical sectional view of the same; Fig. 3 is a view similar to Fig. 2 but at right angles thereto; Fig. 4 is a horizontal sectional view on the line 4—4 of Fig. 3; Fig. 5 is a horizontal sectional view on the line 5—5 of Fig. 3; Fig. 6 is a horizontal sectional view on the line 6—6 of Fig. 2; Fig. 7 is a developed sectional view showing the valve mechanism for controlling the flow of liquid in the door check and Fig. 8 is an enlarged front elevation of a part of the door check.

In a helical torsion spring the direction of wind up may be reversed by holding the spring in the same relative position and reversing the anchoring of the two ends; in other words, if the spring is anchored at its lower end and can be wound up by turning or twisting the upper end in a right hand or clockwise direction as seen from above; then if the upper or top end of the spring is anchored, the same kind of strain can be put on the coils as before if the lower end of the spring is rotated or twisted in the reverse or counter clockwise direction. With this principle in mind, I have provided a door check which is adapted for use on either right hand or left hand doors without replacement or substitution of parts and in which the direction of wind up of the spring may be reversed by means of a very simple adjustment.

Referring now to the drawings the reference character 1 designates a cup shaped casing, the top of which is exteriorly threaded

to receive a cap 2 as shown in Fig. 2. The lower end of the casing 1 tapers inwardly as shown in Fig. 2. Arranged within the casing 1 is a shaft 3 the lower end 4 of which is reduced and flattened on one side as shown 55 at 5 in Figs. 2 and 5, the purpose of which will hereinafter appear. The casing 1 is annular in cross section and the lower end of the same is reduced as shown most clearly in Figs. 1, 2 and 3. Fitting within the casing 1 60 is a sleeve or spring barrel 7, the upper end of which is reduced and projects through the top of the casing 1. The lower end of the sleeve or barrel 7 fits snugly within the reduced lower end of the casing 1. The spring 65 barrel 7 arranged as described divides the casing 1 into an inner compartment 8 and an outer compartment 9. A locking washer 10 having a projection 11 thereon is pressed onto the reduced lower end of the shaft 3 so as to 70 be rigid therewith. A lower spring anchor 12 is rotatably mounted on the lower end of shaft 3 and has a lug 13 formed thereon which engages with a projection 11 on washer 10 when the spring anchor 12 is rotated relative 75 to the shaft 3 in a manner to be more fully described hereinafter. The spring barrel 7 is provided with a projection 7^a which engages with the projection 13 (see Fig. 5) to provide a driving connection between the 80 spring barrel 7 and spring anchor 12, the purpose of which will hereinafter appear.

Fitting over the upper end of shaft 3 and rotatable thereon is an upper spring anchor 14 having a downwardly extending projection 15 thereon which is adapted to engage a pin 16 in shaft 3 in a manner to be hereinafter more fully described. Fitted within the upper end of spring barrel 7 is a driving thimble 17 which is rigidly connected with 85 the spring barrel 7. The driving thimble 17 which is rigidly connected with the spring barrel 7. The driving thimble 17 is provided with a depending lug 18 which 90 engages with an upwardly extending projection 19 formed on the upper side of the upper spring anchor 14.

Arranged within the spring barrel or sleeve 7 is a helical torsion spring 20 the lower end 95 of which is positioned within a slot in the 100

lower spring anchor 12 and the upper end of which is engaged in a slot in the upper spring anchor 14. The cap 2 is provided with an annular upstanding shoulder 21 which fits snugly around the reduced upper end of barrel 7 and which is exteriorly threaded to receive a nut 22 and packing 23. Non-rotatably connected with the upper end of barrel 7 is a door lever 24 which is held in place by a lock nut 25. It will thus be seen that the door lever 24, barrel 7 and thimble 17 move in unison.

Fitting over the lower end of the shaft 3 is a cup 26 the periphery of which is knurled and which is provided with a projection 27. The cup 26 is non-rotatably secured over the shaft 3 and serves as a means for turning the shaft. The cup 26 is secured in place by means of an acorn nut 28 which clamps the cup against the housing or casing 1.

Arranged within the outer annular chamber 9 and rigidly connected with the outer wall 1 is an annular block 29 having therein a bore or passageway 30. Connecting the channel 30 with the interior of the chamber 9 are a pair of oppositely disposed bores or passageways 31 and 32. A second pair of bores or passageways 33 and 34 are also provided in the block 29 and arranged within ball valves 35 and 36 which are held within the bores by pins 35' and 36'.

Arranged within the upper portion of the chamber 9 is an annular block 37 having a downwardly extending portion 38 the lower end of which is reduced as shown at 39. The downwardly projecting portion 38 is somewhat arcuate in shape and fits snugly within the chamber 9, the reduced lower end 39 fitting within a notch in the block 29 as shown in Fig. 7. The upper side of the block 37 is provided with a recess in which is arranged a compression coil spring 40 which serves to hold the reduced lower end 39 in engagement with the notch in the block 29. Also arranged within the chamber 9 is a valve member or vane 41 which is pivotally secured to the spring barrel 7 by means of a pair of plates 42 and 43. The valve member or vane 41 is somewhat arcuate in shape as seen in Fig. 6 so as to frictionally engage and conform to the shape of the outer wall 1. A plate 44 is secured to the casing 1 by any suitable means and is provided with a plurality of openings 45 adapted to receive screws therethrough for securing the check in place. The chamber 9 is adapted to be filled with a liquid the purpose of which is to cushion or check the closing action of the door on which the check is used. The reduced lower end 6 of the casing is provided with suitable indicia for indicating the position at which the cup 26 is to be set for right or left hand doors. The parts are assembled

as hereinbefore described and the operation of the device is as follows:

Assuming that the check is secured in place on a right hand door, that is, a door that opens toward the right, the door lever 24 will be moved and with it the spring barrel 7 and driving thimble 17. Lug 18 on thimble 17 will engage lug 19 on upper spring anchor 14 and rotate the same counter clockwise as seen in Figs. 3 and 4. Projection 15 on spring anchor 14 moves away from pin 16 in shaft 3. Projection 11 on lock washer 10 engages projection 13 on lower spring anchor 12 and holds the lower spring anchor against turning. As the opposite ends of the spring 20 are engaged in slots in the upper and lower spring anchors 14 and 12 respectively, it will be seen that the spring will be wound up from the top or upper end. As the spring barrel is rotated, the vane 41 which is secured thereto is also rotated. The liquid in the chamber 9 in front of the vane escapes through the passages 32 and 31 into the bore or channel 30 and up through the passageway 33 past the valve 35 to the opposite side of the vane. When the door has been opened to its fullest extent the spring 20 is placed under its maximum tension and when the door is released the spring tends to return the parts to their original position. That portion of the chamber 9 between the vane 41 and the abutment or projection 38 is now filled with liquid. This liquid serves to cushion and check the closing of the door. The trapped liquid will escape through the passageway 32, and also through passageway 31 if the door has been opened to its fullest extent, and into the channel 30 and up through the passageway 34 past the valve 36 to the opposite side of the vane 41. After the vane in its return movement has moved beyond both ports 31 and 32, the pressure of the liquid against the upper block 37 will push the same upwardly against the tension of the spring 40 and the liquid will escape past and around the lower end of the projection 38 to the opposite side of the vane. It will thus be seen that the maximum checking action is obtained during the last stage of the closing movement of the door. The edges of the bores 31 and 32 are slightly beveled as shown in Figs. 6 and 7 so that this checking action will be gradual instead of sudden as the flow through the ports 31 and 32, as the case may be, will be cut off gradually.

In order to adapt the check for use on a door which opens toward the left, it is merely necessary to loosen the acorn nut 28 and turn the cup 26 toward the right as seen in Fig. 1 until the projection 27 is opposite the character L on the surface 6. This movement of the cup 6 turns the shaft 3 and its associated parts including the spring 20 and spring barrel 7 and the vane 41 until the vane is positioned on the opposite side of the chamber

9 from that shown in Fig. 6. The clamping nut 28 will now be tightened and will produce sufficient friction between the cup and housing to hold the cup against the wind up load of the spring. Now, should the door lever 24 be moved toward the left, the spring barrel will be moved clockwise as seen in Figs. 4 and 5. The lug 18 will move away from lug 19 and lug 7^a will engage projection 13 on lower spring anchor 12 and turn the lower spring anchor. The pin 16 in shaft 3 will engage projection 15 and hold the upper spring anchor against turning and the spring 20 will be wound from the bottom. 10 The operation of the vane 41 will be the same as hereinbefore described except that it will be moved in the opposite direction.

It will now be clear that I have provided a door check which will accomplish the objects of the invention as hereinbefore stated. Various changes may be made in the details of my construction without departing from the spirit of my invention and I wish my invention to be limited only in accordance 20 with the scope of the appended claims.

Having thus described my invention, what I claim is:—

1. A door check of the class described comprising a casing adapted to contain a liquid, 30 a spring barrel dividing the casing into an inner compartment and an outer compartment and having a portion projecting through said casing and adapted to be connected to a door lever, a shaft arranged with- 35 in said spring barrel and having upper and lower spring anchors rotatably mounted thereon, a coil spring encircling said shaft and having its upper and lower ends connected to said upper and lower anchors re- 40 spectively, manually operable means carried by said shaft and adapted to be selectively positioned to form a driving connection be- 45 tween said spring barrel and either said upper or said lower spring anchors and to hold the opposite spring anchor from turning, a 50 vane arranged within said outer compartment and secured to said spring barrel and means for checking the movement of said vane in one direction.
2. A door check of the class described comprising a casing, a spring barrel arranged within said casing and dividing the same into inner and outer compartments and having a portion projecting through said cas- 55 ing, a door lever non-rotatably connected to said spring barrel, a shaft arranged within said inner compartment and having upper and lower spring anchors rotatably mounted thereon, a coil spring encircling said shaft 60 and having its upper and lower ends connected with said upper and lower spring anchors respectively, manually operable means adapted to be selectively positioned to form a driving connection between said spring 65 barrel and either of said spring anchors and

to prevent the opposite spring anchor from turning whereby said spring may be wound up from either end and means arranged within said outer compartment for resisting the return movement of said spring.

3. A door check of the class described comprising a casing, a spring barrel arranged within said casing and dividing the same into inner and outer compartments, a door lever non-rotatably connected to said spring barrel, a shaft arranged within said inner compartment and having upper and lower spring anchors rotatably secured thereon, a coil spring surrounding said shaft and having its upper and lower ends connected with said upper and lower spring anchors respectively, manually operable means associated with said shaft and spring barrel adapted to be selectively positioned to form a driving connection between said spring barrel and either 80 of said spring anchors and to prevent the opposite spring anchor from turning whereby said spring may be wound up from either end, and means arranged within said outer compartment for resisting the return move- 85 ment of said spring.

4. A door check of the class described comprising a casing, a spring barrel arranged within said casing and dividing the same into a pair of compartments and having a portion 90 projecting through the upper end of said casing, a door lever non-rotatably secured to said projecting portion, a shaft arranged within said spring barrel, a coil spring encircling said shaft, spring anchors arranged upon opposite ends of said shaft and connected with the opposite ends of said spring re- 95 spectively, manually operable means carried by said shaft and operable from the exterior of said casing and adapted to be selectively positioned to connect said spring barrel with either one of said spring anchors and to hold the other spring anchor against turning whereby said spring may be wound up from either end selectively.

5. A door check of the class described comprising a casing, a spring barrel arranged within said casing, a chamber formed by said spring barrel and casing and adapted to be filled with a liquid, a vane ar- 110 ranged within said chamber and secured to said spring barrel and adapted to traverse the space between the wall of said casing and said spring barrel, a coil spring arranged within said spring barrel and adapted to be 115 tensioned when said drum is moved in either direction and means arranged within said spring barrel and adjustable to different positions whereby to connect said spring barrel with either the upper or the lower end of 120 said spring.

6. A door check of the class described comprising a casing, a spring barrel arranged within said casing and dividing the same into a pair of compartments, a shaft 130

- arranged within one of said compartments, a vane arranged within the other compartment and connected with said spring barrel, a door lever connected with said spring barrel whereby the same may be rotated, and manually operable means carried by said shaft and adjustable to different positions to connect said spring barrel with either the upper or the lower end of said spring.
- 10 7. In a door check, the combination of a casing having a pair of compartments, a spring barrel arranged within said casing, a coil spring arranged within said spring barrel and manually operable means arranged within said casing and operable from the exterior thereof and adapted to be selectively positioned so as to connect either end of said spring with said spring barrel and to hold the opposite end of said spring against turning whereby said spring may be wound up from either end.
8. In a door check, the combination of a casing, a spring barrel arranged within said casing, a coil spring arranged within said spring barrel and manually operable means operable from the exterior of said casing and adapted to be selectively positioned to connect either end of said spring with said spring barrel and to hold the opposite end of said spring against turning whereby said spring may be wound up from either end.
- 25 9. In a door check, the combination of a casing, a spring barrel arranged within said casing and dividing the same into a pair of compartments, a door lever connected with said spring barrel, a spring arranged within said spring barrel, manually operable means arranged within said spring barrel and operable from the exterior thereof for selectively connecting either end of said spring with said spring barrel whereby the same is tensioned when said door lever is moved, and means for checking the return movement of said spring.
- 30 10. In a door check, a casing, a spring barrel arranged within said casing, a coil spring arranged within said spring barrel and adapted to be tensioned when said spring barrel is turned in one direction, said spring barrel having a portion extending through said casing and adapted to be connected with a door lever, manually operable means adapted to be selectively positioned to connect said spring barrel with either end of said coil spring and to hold the opposite end of said spring against turning.
- 35 11. In a door check, a casing, a spring barrel arranged within said casing and dividing the same into a pair of compartments adapted to be filled with a liquid, a vane arranged within one of said compartments and pivotally secured to said spring barrel, a coil spring arranged within said spring barrel, manually operable means adapted to be selectively positioned so as to connect
- 5 55 said spring barrel with either end of said coil spring and to hold the opposite end of said coil spring against turning.
12. In a door check, a casing having a pair of compartments, a spring barrel arranged within said casing, an oscillatory vane arranged within one of said compartments and connected with said spring barrel, means for turning said spring barrel, a coil spring arranged within said spring barrel, manually operable means adapted to be selectively positioned to connect said spring barrel with either end of said spring and to hold the opposite end of said spring against turning whereby said spring may be wound up from either end when said spring barrel is turned and means for regulating the return movement of said spring barrel and oscillatory vane.
13. In a door check, the combination of a casing, a tubular member arranged within said casing and dividing the same into a pair of compartments, a shaft arranged within one of said compartments, a door lever non-rotatably connected with said drum, a coil spring encircling said shaft, means forming a driving connection between said tubular member and spring and embodying manually operable adjustable means for connecting either the upper or lower end of said spring with said tubular member whereby said spring may be wound up from the top or from the bottom.
14. In a door check, the combination of a casing, a spring barrel arranged within said casing and dividing the same into an inner and an outer compartment, a shaft arranged within said inner compartment, a coil spring encircling said shaft, a vane disposed within said outer compartment and pivotally connected with said spring barrel, said outer compartment being adapted to be filled with liquid, and adjustable means mounted on the lower end of said casing for connecting said spring barrel with either the upper or the lower end of said spring.
15. In a door check, a casing having a pair of compartments, a spring barrel arranged within said casing, an oscillatory vane arranged within one of said compartments and secured to said spring barrel, means for oscillating said spring barrel, a coil spring for returning said spring barrel to its original position and means arranged within said casing and movable to different positions to connect said spring barrel with either the upper or the lower end of said spring.
16. A hydraulic check comprising a casing, a spring barrel arranged within said casing and having a portion projecting through said casing, a shaft arranged within said spring barrel and having upper and lower spring anchors rotatably mounted thereon, a coil spring encircling said shaft and having its upper and lower ends connected to said up-

- per and lower anchors respectively and manually operable means carried by said shaft and operable from the exterior of said casing and adapted to be selectively positioned 5 to form a driving connection between said spring barrel and either said upper or said lower spring anchors and to hold the opposite spring anchor from turning.
17. In a hydraulic check, a casing, a spring 10 barrel arranged within said casing and dividing the same into a pair of compartments adapted to contain a liquid, a vane arranged within one of said compartments and operatively connected with said spring barrel, a coil spring arranged within said spring barrel and manually operable means operable from the exterior of said casing and adapted to be selectively positioned so as to connect said spring barrel with either the upper or the 15 lower end of said coil spring and to hold the opposite end of said coil spring against turning, and means for imparting a turning movement to said tubular member.
18. In a door check, a casing having a pair 20 of compartments, a spring barrel arranged within said casing, an oscillatory vane arranged within one of said compartments and connected with said spring barrel, means for turning said spring barrel, a coil spring arranged within said spring barrel, manually 25 operable means adapted to be selectively positioned to connect said spring barrel with either the upper or the lower end of said spring and to hold the opposite end of said spring against turning whereby said spring 30 may be wound up from either end when said spring barrel is turned.
19. In a door check, the combination of a casing, a spring barrel arranged within said casing and dividing the same into an inner 35 and an outer compartment, a shaft arranged within said inner compartment, a coil spring encircling said shaft, a vane disposed within said outer compartment and connected with said spring barrel, said outer compartment 40 being adapted to be filled with liquid, and adjustable means forming a driving connection between said spring barrel and either the upper or the lower end of said spring.
20. A hydraulic check comprising a casing 45 adapted to contain a liquid, a tubular member arranged within said casing and dividing the same into a pair of compartments, a vane arranged within one of said compartments and operatively connected with said tubular member, a coil spring arranged within the other of said compartments and manually 50 operable means operable from the exterior of said casing and adapted to be selectively positioned to operatively connect said tubular member with either the upper or the lower end of said coil spring and to hold the opposite end of said coil spring against turning whereby said spring 55 may be wound up from either end, and means for imparting a turning movement to said tubular member.
21. In a hydraulic check the combination of a casing adapted to contain a liquid, a tubular member arranged within said casing and cooperating therewith to form a compression chamber, a vane arranged within said compression chamber and operatively connected with said tubular member, an abutment arranged within said compression chamber and non-rotatably secured therein and adapted to be lifted when the pressure 60 within the chamber reaches a predetermined amount, a coil spring arranged within said tubular member, and means adapted to be selectively positioned to form a driving connection between said tubular member and either end of said coil spring and to hold the opposite end of said coil spring against turning, and means for imparting a turning movement to said tubular member.
22. In a door check, the combination of a casing, a spring barrel arranged within said casing and dividing the same into an inner 65 and an outer compartment, a shaft arranged within said inner compartment, a coil spring encircling said shaft, a vane disposed within said outer compartment and connected with said spring barrel, said outer compartment being adapted to be filled with liquid, and adjustable means mounted on the lower end of said casing for connecting said spring barrel with either the upper or the lower end of said spring.
23. In a hydraulic check, the combination of a casing adapted to contain a liquid, a tubular member arranged within said casing, and cooperating therewith to define a compression chamber, a vane arranged within said compression chamber and operatively connected with said tubular member, an abutment disposed within said compression chamber and non-rotatably secured therein, a coil spring arranged within said casing and means adapted to be selectively positioned to form a driving connection between said tubular member and either end of said coil spring and to hold the opposite end of said coil spring against turning, and means for imparting a turning movement to said tubular member.
24. In a hydraulic check, the combination of a casing adapted to contain a liquid, a tubular member arranged within said casing, and cooperating therewith to define a compression chamber, a vane arranged within said compression chamber and operatively connected with said tubular member, an abutment disposed within said compression chamber and non-rotatably secured therein, a coil spring arranged within said casing and means adapted to be selectively positioned to form a driving connection between said tubular member and either end of said coil spring and to hold the opposite end of said coil spring against turning, and means for imparting a turning movement to said tubular member.

member, and means within said casing whereby the maximum checking action is obtained during the latter part of the movement of said vane in either direction.

- 5 25. In a hydraulic check, the combination of a casing adapted to contain a liquid, a tubular member arranged within said casing, and cooperating therewith to define a compression chamber, a vane arranged within
10 said compression chamber and operatively connected with said tubular member, an abutment disposed within said compression chamber and non-rotatably secured therein, a coil spring arranged within said casing and
15 means adapted to be selectively positioned to form a driving connection between said tubular member and either end of said coil spring and to hold the opposite end of said coil spring against turning, and means for imparting a turning movement to said tubular member, and means within said casing whereby the checking action will be progressively increased and reach its maximum during the
20 last part of the movement of said vane.
25 In testimony whereof, I hereunto affix my signature.

COURTNEY N. MITCHELL.
